United States Patent Office.

D. H. HEYEN, OF NEW YORK, N. Y.

Letters Patent No. 71,755, dated December 3, 1867.

IMPROVED LIFE-PRESERVER.

The Schedule referred to in these Letters Patent and making part of the same.

TO ALL WHOM IT MAY CONCERN:

Be it known that I, D. H. HEYEN, of the city, county, and State of New York, have invented a new and useful Improvement in Life-Preservers; and I do hereby declare that the following is a full, clear, and exact description thereof, which will enable those skilled in the art to make and use the same, reference being had to the accompanying drawings, forming part of this specification.

This invention relates to a new and improved method of constructing life-preservers, whereby they are made much more effectual in case of need, and much less liable to injury from accident; and the invention consists in combining an elastic air-tight tube with a broad substantial belt, thereby effectually protecting the air-tube from injury, and rendering its application to the purpose intended much more easy than where air-tubes or vessels are attached directly to the body as life-preservers without such support.

Figure 1 represents the life-preserved complete and ready to be attached to the body.

Figure 2 is a view of the same when so attached.

Similar letters of reference indicate corresponding parts.

A represents a belt of cloth or of some other light and substantial material, arranged with buckles and straps for securing the same around the body, as seen in the drawing. B represents an air-tight elastic tube, formed of rubber or of some other suitable material, and attached to the belt in sinuous or serpentine form by clips marked C, as seen in the drawing. These clips are elastic, so that they expand with the air-tube when the tube is filled with air. When not filled, the tube and the clips will lie flat upon the belt, so that the belt may be worn under the clothes around the body, and be inflated as occasion may require. Upon the outer end of the tube there is a mouth-piece and valve, through which the air is introduced, and by which it is confined when the tube is inflated.

In applying the life-preserved, it is buckled around the body, with the air-tube on the outside, as seen in the drawing, where it may be worn (as before stated) when on the water, as an ever-ready safeguard in case of accident or danger.

Having thus described my invention, what I claim as new, and desire to secure by Letters Patent, is—

The air-tube B, in combination with the belt A, attached and arranged substantially as shown and described for the purpose set forth.

The above specification of my invention signed by me, this 21st day of June, 1867.

D. H. HEYEN.
